CLAIM

The ornamental design for an enclosed transportable water purification apparatus, as described and shown.

DESCRIPTION

FIG. 1 is a right, rear perspective view of an enclosed transportable water purification apparatus embodying my new design, the broken line drawing of a trailer is for illustrative purposes only and forms no part of the claimed design;

FIG. 2 is a top plan view of the enclosed transportable water purification apparatus of FIG. 1;

FIG. 3 is a bottom plan view thereof;

FIG. 4 is a front end elevational view thereof;

FIG. 5 is a back end elevational view thereof;

FIG. 6 is a right side elevational view thereof; and,

FIG. 7 is a left side elevational view thereof.

The broken line drawings of an outlet hose in FIGS. 4 and 5 are for illustrative purposes only and form no part of the claimed design.

FIG.1

FIG.2

FIG.3

FIG. 4

FIG. 5

FIG. 6

FIG. 7
